UNITED STATES PATENT OFFICE.

FRANCIS MEISEL, OF BOSTON, MASSACHUSETTS, ASSIGNOR TO THE KIDDER PRESS MANUFACTURING COMPANY, OF SAME PLACE.

VIBRATOR-ROLL FOR PRINTING-MACHINES.

SPECIFICATION forming part of Letters Patent No. 580,984, dated April 20, 1897.

Application filed May 15, 1896. Serial No. 591,679. (No model.)

To all whom it may concern:

Be it known that I, FRANCIS MEISEL, a citizen of the United States, residing at Boston, in the county of Suffolk and State of Massachusetts, have invented certain Improvements in Mechanism for Giving Endwise Motion to the Vibrator-Rolls for Printing-Machines, of which the following is a full, clear, and exact description, reference being had to the accompanying drawings, making part of this specification, in which—

Figure 1 is a side elevation of a rotary web-printing machine having my improved vibrator-roll mechanism applied thereto. Fig. 2 is an enlarged sectional detail on the line 2 2 of Fig. 1, looking outward in the direction of the arrow 10. Fig. 3 is a side elevation of the parts shown in Fig. 2. Fig. 4 is an enlarged detail of one of the oscillating bevel-wheels 20 and parts connected therewith, looking inward in the direction of the arrow 12, Fig. 1.

My invention has for its object to provide a simple and effective mechanism for giving endwise motion to the vibrator-rolls of printing-machines, said mechanism being particularly adapted for use on machines in which the "form" from which the impression is made is in cylindrical shape, commonly termed "rotary printing-machines."

To this end my invention consists in operating the rocker-levers from which endwise motion is transmitted to the vibrator-rolls by means of oscillating bevel-wheels lying in a plane parallel with the plane in which the end 35 of the printing-cylinder lies and receiving motion through suitable connections from the driving-shaft, said bevel-gears meshing with sector-gears on said rocker-levers, whereby all the vibrator-rolls throughout the machine 40 are simultaneously operated in a simple and convenient manner from a single shaft, as hereinafter more particularly described.

In the said drawings, A represents the framework of a rotary printing-machine, around 45 which are arranged a series of pairs of form and impression cylinders B C, Fig. 2, the ends of said cylinders being shown by dotted lines in Fig. 1.

The web of paper shown dotted in Fig. 1 50 is drawn from a roll D and passes between the several pairs of form and impression cyl-

inders, by which the impressions are produced in the usual manner. Each form-cylinder is provided with the usual inking apparatus, consisting of form-rollers, distributing-cylinders, vibrator-rolls, &c., which are rotated by suitable gears receiving motion from the gear on the shaft of the form-cylinder. The shafts *a* of the vibrator-rolls *G*, one of which is shown in Fig. 2, are rotated by means of suitable gears, and to these vibrator-rolls endwise motion is given by mechanism which will now be described. To the outer end of one of the shafts *b* of the machine, which is connected with the driving-shaft by a train of gears, is secured outside the framework a disk *c* to a crank-pin *d*, on which are pivoted two connecting-rods *e*, the opposite ends of which are respectively pivoted to two bevel-wheels *H H*, mounted on studs *g*, projecting from a casting *A'*, bolted to the framework *A*, said studs being arranged in line with the axes of the form-cylinders, whereby as the disk *c* is rotated an oscillating movement is imparted to said wheels *H H*, which are provided at their peripheries with bevel-teeth *h*. These wheels are preferably provided with teeth at certain portions only of their peripheries, as shown, but the teeth may extend entirely around the wheels, if desired.

The bevel-wheels *H H* are caused to oscillate other similar toothed bevel-wheels *H* by means of connecting-rods *k*, and one of the latter bevel-wheels is connected to still another bevel-wheel *H* by a rod *m*, as shown at 85 the right-hand side of Fig. 1, and in this manner any desired number of similar bevel-wheels arranged around the machine can be simultaneously oscillated from a single driving-shaft.

Each bevel-wheel *H* gives endwise motion to the several vibrator-rolls *G* of the inking apparatus of a single-form cylinder in the following manner: *K* is a double-ended rocker-lever which is pivoted on a stud projecting 95 radially from the casting *A'* in a plane at right angles to the axis of the stud *g*, on which the bevel-wheel *H* oscillates, said rocker-lever being provided at the center with a sector bevel-gear *f*, meshing with the wheel *H*, as shown in Figs. 1 and 4, said rocker-lever being provided at its two opposite ends

with oscillating projections *n*, which engage grooved disks *6*, secured to the ends of the shafts *a* of a pair of vibrator-rolls *G*, as shown in Fig. 4, which are thus reciprocated in the direction of their length as the wheel *H* is oscillated by the means described.

L is another rocker-lever, which is also pivoted on a radial stud projecting from the casting *A'* at right angles to the stud *g*, said rocker-lever *L* being provided with a sector-gear *8*, Figs. 2 and 3, also meshing with the teeth of the oscillating wheel *H*, this lever *L* being connected by a rod *r* with an arm *15*, Fig. 2, secured to the end of a rocker-shaft *s*, supported in suitable bearings projecting from a bracket *t*, secured to the framework *A*. To this rocker-shaft *s* are secured two short arms *16* *18*, as shown in Fig. 1, the arm *16* having an oscillating projection *20*, which engages a grooved disk *w* at the end of another vibrator-roll, and the arm *18* having a similar projection *20*, which engages a grooved disk on one of another pair of vibrator-rolls connected to reciprocate in opposite directions by a double-ended rocker-arm *22*, so that as the shaft *s* is rocked the vibrator-rolls connected therewith will be reciprocated simultaneously with the pair actuated by the rocker-lever *K*, as previously described, and in this manner all the vibrator-rolls throughout the machine are simultaneously reciprocated in the direction of their length as the disk *c* is rotated. I do not wish to limit myself to the number of vibrator-rolls operated from a single oscillating bevel-wheel *H*, as the number may be increased or diminished without departing from the spirit of my invention.

If more rolls are required, as many rocker-levers may be arranged around and to mesh with a single bevel-wheel *H* as its circumference will properly accommodate, the casting *A'* being provided with a radial stud similar to those above described for each rocker-lever, or each rocker-lever may be made to operate more vibrator-rolls by means of suitable connections similar to those shown and described.

What I claim as my invention, and desire to secure by Letters Patent, is—

1. In a printing-machine, the combination with the printing-cylinder, of a vibrator-roll, an oscillating toothed bevel-wheel lying in a plane parallel with the plane in which the end of the printing-cylinder lies, a rocker-lever having a sector-gear meshing with said bevel-wheel and suitable connections between the rocker-lever and the vibrator-roll, whereby the latter is reciprocated in the direction of its length as the bevel-wheel is oscillated, substantially as set forth.

2. In a printing-machine, the combination with the printing-cylinder, of the vibrator-

rolls and their shafts, an oscillating toothed bevel-wheel lying in a plane parallel with the plane in which the end of the printing-cylinder lies and means for actuating the same, rocker-levers provided with sector-gears meshing with said bevel-wheel, and suitable connections between the rocker-levers and the vibrator-rolls, whereby the latter are reciprocated in the direction of their length as the bevel-wheel is oscillated, substantially as set forth.

3. In a printing-machine, the combination with the printing-cylinder, of the vibrator-rolls and their shafts, an oscillating toothed bevel-wheel lying in a plane parallel with the plane in which the end of the printing-cylinder lies and means for actuating the same, rocker-levers provided with sector-gears meshing with said bevel-wheel, said rocker-levers being mounted on studs arranged radially with respect to the stud on which said bevel-wheel is mounted and at right angles thereto, and suitable connections between the rocker-levers and the vibrator-rolls, whereby the latter are reciprocated in the direction of their length as the bevel-wheel is oscillated, substantially as set forth.

4. In a printing-machine, the combination with the printing-cylinder, of a pair of vibrator-rolls and their shafts, the latter provided at their ends with grooved disks, an oscillating toothed bevel-wheel lying in a plane parallel with the plane in which the end of the printing-cylinder lies and means for actuating the same, a double-ended centrally-pivoted rocker-lever having projections engaging the grooved disks of the shafts of the vibrator-rolls, and provided with a sector-gear meshing with said oscillating wheel, whereby the vibrator-rolls are reciprocated in the direction of their length as the bevel-wheel is oscillated, substantially as described.

5. In a printing-machine, the combination with the several sets of vibrator-rolls, of a series of oscillating toothed bevel-wheels and suitable connections, whereby motion is transmitted to all of said bevel-wheels from a single shaft, rocker-levers provided with sector-gears meshing with said oscillating bevel-wheels, and suitable connections between said rocker-levers and the shafts of the vibrator-rolls, whereby the latter are reciprocated in the direction of their length as the bevel-wheels are oscillated, substantially as set forth.

Witness my hand this 9th day of May, A. D. 1896.

FRANCIS MEISEL.

In presence of—

P. E. TESCHEMACHER,
A. R. ELLINGWOOD.
